Attn:

UNITED STATES PATENT OFFICE.

GEORGE WILKINSON, OF PROVIDENCE, RHODE ISLAND.

DESIGN FOR A HANDLE FOR SPOONS, &c.

SPECIFICATION forming part of Design No. 22,749, dated August 29, 1893.

Application filed July 28, 1893. Serial No. 481,774. Term of patent 7 years.

To all whom it may concern:

Be it known that I, GEORGE WILKINSON, of Providence, in the county of Providence and State of Rhode Island, have invented and produced a new and original Design for Handles of Spoons or Similar Articles, of which the following is a specification, reference being had to the accompanying drawing, forming part thereof.

10 The drawing is a representation of a handle attached to the bowl of a spoon and illustrating my new design.

The leading features of my new design for handles of spoons and similar articles consist 15 in the symmetrical wave-like outlines of the handle forming alternating enlargements and contractions and gradually increasing the width of the same toward the upper end,—surface ornamentation consisting of a foliated 20 ornament, bound across the center, displayed at the base of the handle,—beadings extending therefrom parallel with the outlines of the neck to the first contractions,—a pyramidal leaf on the first enlargement above the neck 25 the apex of which extends on to the second enlargement,—floral ornaments depending from the base of this leaf,—foliated beaded borders extending along the edges of the second enlargement inclosing a plain panel and a 30 scrolled ornament at the top of the handle.

In the drawing 2 represents the handle of a spoon of which 3 represents the bowl. The outline of the handle first curves inward from the bowl, or other article, secured to its base

4, then gradually outward forming the neck 35 5, then abruptly inward, again outward and inward forming the first enlargement 6, then abruptly outward for a short distance, then gradually curving outward and finally inward to form the second enlargement 7 and the top 40 of the handle 8. At the base of the handle is displayed the foliated-ornament 9 crossed by the beadings 10. From this ornament the beadings 11—11 extend upward, following the outline of the neck, ending in outwardly 45 scrolled ends just below the first enlargement. On this enlargement is represented a pyramidal leaf 12 the apex of which extends into the plain portion of the upper panel and from the base of the leaf is pendent the floral ornament 13 extending on to the plain central portion of the neck. The edges of the enlargement 6 are finished in beadings 14—14. Extending along the edges of the enlargement 7 and inclosing the plain panel 15 are the foliations 16—16 between beadings 17—17. These borders curve over the upper portion of the handle and end in the group of scrolled ornaments 18.

What I claim is—

The design for handles of spoons and similar articles as herein shown and described.

In witness whereof I have hereunto set my hand.

GEORGE WILKINSON.
